UNITED STATES PATENT OFFICE.

EDWARD SEITZ, OF PEORIA, ILLINOIS, ASSIGNOR OF ONE-HALF TO JAMES E. LOCKWOOD,
OF PEORIA, ILLINOIS.

VAPOR-LAMP.

No. 905,467.

Specification of Letters Patent.

Patented Dec. 1, 1908.

Application filed September 11, 1905. Serial No. 277,850.

To all whom it may concern:

Be it known that I, EDWARD SEITZ, citizen of the United States, residing at Peoria, in the county of Peoria and State of Illinois, have invented certain new and useful Improvements in Vapor-Lamps; and I do hereby declare that the following is a full, clear, and exact description of the invention, which will enable others skilled in the art to which it appertains to make and use the same.

This invention pertains to improvements in vapor lamps.

One of the objects of the invention is to provide a vapor generator immediately above the burner and having connected directly therewith a hydro-carbon fluid conducting member for introducing the fluid immediately into such generator.

I am aware that it is not new to provide a vapor generator immediately above the burner nor to introduce fluid into a generator, but the particular arrangement which I show and describe herein I believe to be new. In devices of this character there is always a vapor jet orifice for discharging vapor into a conducting member communicating with the burner, there also being an air space between the orifice and the conducting member to provide for proper mixture of vapor and air, and it is my purpose in connection with the air space just mentioned, as one of my objects, to provide a conducting member by which to carry away from the air-space, and from the jet orifice, any fluid that may not have become vaporized, such member leading the fluid away from the vicinity of the burner to thereby avoid the danger of possible ignition of the fluid from the burner.

It is also an object to provide a peculiar form of cast member through which to convey the vapor and through which also to convey the fluid before being formed into vapor, the fluid being heated from the heated vapor as it passes to the burner, all of which will be pointed out in the accompanying claims.

In the appended drawing, Figure 1 is an elevation of my improved lamp. Fig. 2 is a sectional elevation of vaporizing device. Fig. 3 is a top view of portion of a needle-valve and mixing chamber and connection therebetween. Fig. 4 is a sectional elevation of a mixing chamber and gasolene conduit. Fig. 5 is a rear elevation of vapor-

mixer showing position of certain parts for permitting removal of a connection between the mixer and needle-valve shown in Fig. 3. Fig. 6 is an elevation of a portion of the top of the lamp-frame showing a suspending hook for the lamp.

My lamp frame consists preferably of lengths of tubing and light tubular castings which are easily and quickly assembled and constitute a frame that is low in cost and quite rigid.

I provide a hook as at A by which to suspend the lamp, and into this is screwed a suitable length of tubing B, the latter being in turn screwed into a casting C which forms the mixing chamber for the vapor as will be described later. Into the lower end of said casting C is screwed a second length of tubing D having at its opposite end a cast elbow, or goose-neck, E into which said tube is also screwed. The upturned free end of the elbow E has the usual Bunsen burner (not indicated) surmounted by a mantle F. It has been the practice heretofore to employ a length of tubing and bend it in the desired manner to form a frame of the shape best suited for a lamp frame. But this process is costly because it consumes much time and for the further reason that many of the tubes are broken in the attempt to bend them. It has therefore been my object among others, to produce a frame that is of low cost and quickly and easily put together. The castings are all of uniform size and shape, merely needing a thread or two into which to screw the uniform lengths of tubing taken from stock. It will be seen that a frame can be put together in a fraction of the time necessary to make the older forms referred to.

I have referred to the casting C as a mixing chamber. It is also a gasolene conduit and may be understood by reference to Fig. 4. It has a passage *a* opening at one side of the casting through an extension C', and extending inward and downward to open into the tube D, in Fig. 1, already described. Cast with the said member C are two horizontal extensions C² and C³ within which is a continuous passage *b* which extends around the passage *a* as shown in Fig. 4 105 there being a wall C⁴ separating said passages. Connected to the extension C³ is a pipe G and controlling valve H, while connected into the extension C² is a horizontal tube J forming part of a vapor-generator K 110

stationed immediately above the mantle F as shown. Said generator, as shown in Fig. 2, consists of a vertical hollow member, having suspended therefrom and preferably 5 cast therewith, an open torch L and radiating heat conducting fingers M. The said member K has a bottom N to form a closed chamber. Above the tube J and also cast with member K is a tube O within which is 10 a needle-valve P for regulating the opening of and for closing an aperture Q in the closed end R of the said tube O. The member K is preferably provided with an asbestos filling S, while the needle-valve P is 15 surrounded with a winding of wire gauze or other form of strainer. The torch L is likewise provided with asbestos or other material that will not burn but will absorb a fluid such, for instance, as gasoline or alcohol. The 20 needle-valve is located just opposite the passage a of the casting C and the vapor passes from the former into the latter under pressure and thence through the pipe D and casting E to the mantle F. As in common practice the jet-orifice Q is separated from the 25 mixing chamber a by an air space, see Fig. 3, whereby the vapor issuing from such orifice can take air into said mixing chamber with it. In some instances this air space is un- 30 protected and in others some sort of means is provided for preventing strong air currents from striking the vapor at this point. I have provided in the present instance a new form of protecting member indicated by 35 the letter T and consists of a cast sleeve having an elbow U formed therewith terminating in a downturned tube V. The sleeve is provided with a notch W for receiving a lug X on the extension C' upon which the 40 sleeve is designed to slip, the lug serving to sustain the sleeve in a stationary position. Provision is made for removing the sleeve T from the lamp and this is accomplished by slipping said sleeve back upon the member 45 O as shown in Fig. 3, then the generator K is swung on the member C by turning the member J in the latter to carry the said member O away from the member C as shown in Fig. 5, the device being viewed 50 from the back of the lamp, the parts G and H being removed from the extension C'. By turning the member J a sufficient distance it will be seen that the sleeve T can be carried clear of the mixer C so as to be 55 slipped on and off when desired.

The advantage in the closed sleeve with the tube V is, that no drafts or air currents can possibly affect the vapor jet but at the same time the needed air for proper combustion 60 at the mantle will be drawn in through said tube V. A further advantage in providing the said tube is that any gasoline not vaporized, should it reach the jet orifice for any reason will fall upon the interior sur- 65 face of the sleeve and by gravity will be

drained out through the tube V far from the mantle, thus minimizing all danger of igniting therefrom. By providing one casting for the vapor ejected from the jet-orifice and the gasoline as it comes from the source 70 of supply, the heated vapor makes the said casting intensely hot and by having the gasoline pass through the heated metal on its way to the generator it is in better condition to be quickly vaporized. In practice 75 the gasoline is admitted to the casting C by means of the controlling valve H, passes through the conduit b into the tube J and thence into the generator K. The torch having previously been supplied with a small 80 quantity of combustible fluid is ignited the flame therefrom serves to quickly raise the generator to a high temperature assisted by the radiating fingers M which conduct the heat to said generator. The fluid having entered the latter is distributed through the asbestos filling and subjected to the intense 85 heat and immediately vaporized and forced by its own expansion upward into and through the needle-valve or jet orifice Q. 90 The vapor is forced across the air space within the sleeve T into the mixing chamber or passage a from whence it passes downward eventually reaching the mantle where it is ignited from the still burning torch 95 above. The casting C through whose passage a the vapor must pass is quickly raised to a high temperature so that the gasoline thereafter passing through the passage b is heated to a high degree before entering the 100 generator where it is more readily converted into the combustible gas. The asbestos serves to strain the particles of foreign matter from the fluid and holds back the paraffin 105 always found in that material, and furthermore the fluid by being carried through the asbestos is quickly spread and by filling the space therein is quickly heated and vaporized and rendered intensely hot. An advantage in having the jet-orifice above the 110 inlet of gasoline at J to the generator is that the resulting vapor is carried to a high elevation and consequently there is little chance for fluid to pass out of the jet orifice with it and is in better condition for burning 115 at the mantle.

An advantage in the method of constructing the lamp frame which I have not heretofore mentioned is the fact that any part of said frame can be removed at any time 120 even by an inexperienced person and a swab pushed through every part of said frame to remove all sediment that may collect therein, whereas in a frame of a single length of tubing this is not practicable. It is to be 125 observed that any and every portion of the frame and fittings throughout the lamp can be easily reached and cleaned.

I am aware that others have produced vapor lamps wherein the vapor is carried off to 130

the burner from above the point where the gasolene is entered by which means, as in mine, the vapor is consequently in drier form but these devices do not have in conjunction with the arrangement mentioned, the peculiar form of cast member C I have described by which to initially heat the fluid before it enters the generator. In my arrangement the single casting C has the two 5 passages *a* and *b* separated by a thin wall and each extending at right angles to one another, the super-heated vapor heating the fluid to a high degree as it passes partially around the vapor passage, the solid metal 10 being kept heated by the hot vapor.

I am also aware that on this class of lamps a sleeve has been employed between the outlet end of the generator and the vapor-receiving tube in the position in which 15 mine is shown but a sleeve having the horizontally positioned tube V with a downturned outer end has not to my knowledge been used.

In my lamp the vertical portion K of the 20 generator being directly over the burner is heated thereby and the flame from its torch is readily communicated to the said burner as the vapor arises around it. The inlet or 25 supply pipe J is also over the burner and is of large size thereby carrying a considerable bulk of gasolene distributed through the filling thereof. In this as well as the member K the fluid is highly heated and vaporized and strained as already stated 30 then passing to the member O which is also of large size thereby providing for a large and unfailing body of vapor under considerable pressure.

By having J and O separate pipes a larger 35 bulk of gasolene can be passed to the generator and consequently a greater amount of vapor can be made and held constantly in reserve which can be drawn from by the burner as needed through the jet orifice. 40 Furthermore, these members J O being separate provide for a larger heating area than would otherwise result by any other construction.

Therefore I claim:—

- 50 1. In a vapor lamp the combination of a vertically positioned hollow vaporizing member provided with a torch at its lower end, a horizontally disposed lower member having a single bore or passage and connected at one end into the said vertical member, and connected at its opposite end with the fluid supply, a second separate upper horizontally disposed member adjacent to the first and having a single bore and connected 55 at one end into the said vertical member and provided with a vapor jet orifice at its other end, both said lower horizontally disposed member and the vertical member having a filling therein for the purposes set forth, a 60 vapor burner positioned directly beneath the 65 vertical member and ignited from its torch, a member for carrying vapor to the burner from the jet orifice in the upper of said horizontally disposed members, there being an opening in the vapor carrying member 70 opposite the jet orifice, a valve for controlling the supply of fluid through the lower of the horizontal members to the vertical member, and a valve for controlling the vapor jet orifice substantially as set forth. 75
2. In a vapor lamp the combination of a vertical vapor generating member having a filling therein, a horizontally disposed conduit connected at one end thereinto and connected at its other end with the fluid supply, a second horizontally disposed conduit above the first and having a single passage therethrough and connected at one end into the said vertical member and having a jet orifice at its other end, a filling material for 80 both said conduits, a valve for controlling the said jet orifice, a valve for controlling the supply of fluid into the first described conduit, a burner directly beneath the vertical member, a member for conveying vapor to the burner and having an opening therein opposite the jet orifice of the upper conduit for receiving vapor from the latter, there being a space between said opening and the jet orifice, a sleeve for inclosing the 85 said space, and a horizontally disposed tubular member connected into said sleeve and extending away from the vicinity of the burner and having a downturned free extremity substantially as described and for 90 the purposes set forth. 95
3. In a vapor lamp, a vertical member provided with a fluid passage the latter being provided with a filling material, a horizontally disposed fluid supplying member connected integrally with the said vertical member and having a passage for connecting with that of the latter and having a filling material therein, a second horizontally disposed member above the first and connected at one end integrally with the vertical member and having a passage connecting with that of the said member and provided with a filling, and having at its opposite end a vapor jet orifice, a valve for controlling the jet orifice, a vapor burner beneath the vertical member, a conduit for conveying vapor to the burner, a vapor receiving member connected with the conduit and provided with a passage connected therewith and opening opposite the jet orifice and also having the fluid supplying member of the vertical member connected therewith, there being a fluid passage in the vapor receiving member partially surrounding the vapor 100 passage thereof and heated by the vapor passing therethrough, a sleeve connected between the vapor receiving member and the member having the orifice, and a horizontally disposed tubular member connected 105 110 115 120 125 130

into said sleeve and extending in a direction away from the burner and having a down-turned free extremity substantially as described and shown.

- 5 4. In a vapor lamp, the combination with a vertical member provided with a passage and a filling, a horizontally disposed fluid conducting member connected at one end thereinto, a second separate member connected at one end also into the vertical member and having a passage connecting with that of the vertical member, and having a filling, there being a jet orifice at its opposite end, a valve for controlling such orifice, a 10 vapor burner directly beneath the vertical member, a member for conducting the vapor to the burner, the vapor-conducting passage of said member opening opposite the jet orifice and receiving vapor therefrom there being an air space between the vapor conducting member and the orifice, there being a fluid passage extending partially around the vapor conducting passage and into which the first or fluid conducting member is connected, and with which also the source of fluid supply is connected, a sleeve mounted on the second described horizontal member and inclosing the space between the jet orifice and the opening opposite thereto, and a 15 tubular member connected into said sleeve and extending outward substantially in a horizontal direction and away from the vicinity of the burner, substantially as set forth.
- 15 5. In a vapor lamp, a vapor conduit having a discharge opening, a vapor burner, a member for conducting vapor thereinto, said vapor conducting member having an opening opposite said discharge opening, there being an air space between the discharge 20 opening and the vapor conducting member, a sleeve slidable upon the vapor conduit and arranged to entirely inclose the space, and a tubular member opening at one end into said

- 25
- 30
- 35
- 40

sleeve and extending horizontally therefrom, and curved downward at its outer free end substantially in the manner described and shown.

6. In a vapor lamp, a vapor conduit, a discharge opening therefor, a vapor burner, a member for conducting vapor thereinto from the said discharge opening, there being an opening in said member opposite the discharge opening and separated therefrom, a sleeve slidable upon the vapor conduit, there being a notch in one end, a lug on the vapor conducting member to engage said notch, and a tubular member connected at one end into the sleeve and extending in a direction away from the burner, and being down-turned at its free end substantially as described and shown.

7. In a vapor lamp, a tubular frame, a burner connected therewith and supplied with vapor therefrom, a vapor-generator above the burner and having two horizontal tubular limbs connected thereinto, one for conveying gasoline and carried by the frame on which it is adapted to rock, the other limb adapted for conveying vapor from the generator and having an end terminating opposite the frame and having a vapor jet orifice therein, there being an opening in the frame opposite the vapor jet orifice, a sleeve carried by the last described limb and adapted to engage the frame, an air inlet tube carried by the sleeve, means for holding the sleeve rigid with respect to the frame and the limb, said sleeve adapted for removal from both substantially in the manner and for the purposes set forth.

In testimony whereof I affix my signature, in presence of two witnesses.

EDWARD SEITZ.
